PARTIALLY DRIED INKJET MEDIA CONDITIONER

BACKGROUND

Inkjet printers can deposit quantities of printing fluid onto a printable media (e.g., paper, plastic, etc.). In some examples, inkjet printers can create a curl and/or cockle in the printed media when the printing fluid droplets deposited by the inkjet printer are not completely dry. In some examples, a number of physical properties of the printable media can be changed when the printing fluid droplets deposited by the inkjet printer are not completely dry. For example, the stiffness of the printable media can be changed when the printing fluid droplets deposited by the inkjet printer are not completely dry. The curl, cockle, and/or other physical properties that change due to the printing fluid droplets can make finishing processes difficult.

BRIEF DESCRIPTION OF THE DRAWINGS

FIG. 1 illustrates an example system for a partially dried inkjet media conditioner consistent with the present disclosure.

FIG. 2 illustrates an example system for a partially dried inkjet media conditioner consistent with the present disclosure.

FIG. 3 illustrates an example system for a partially dried inkjet media conditioner consistent with the present disclosure.

FIG. 4 illustrates an example system for a partially dried inkjet media conditioner consistent with the present disclosure.

FIG. 5 illustrates an example system for a partially dried inkjet media conditioner consistent with the present disclosure.

FIG. 6 illustrates an example system for a partially dried inkjet media conditioner consistent with the present disclosure.

FIG. 7 illustrates an example system for a partially dried inkjet media conditioner consistent with the present disclosure.

FIG. 8 illustrates an example system for a partially dried inkjet media conditioner consistent with the present disclosure.

FIG. 9 illustrates an example system for a heated pressure roller consistent with the present disclosure.

DETAILED DESCRIPTION

A number of systems and devices for a partially dried inkjet media conditioner are described herein. In some examples, a partially dried inkjet media conditioner can include: a print engine that encases a print zone within a housing, and a media path to provide partially dried inkjet media from the print zone to a conditioner within the print engine, wherein the conditioner comprises a heated pressure roller. As used herein, partially dried inkjet media can include media with applied printing fluid from an inkjet type printing device that is not completely dried on the media.

The partially dried inkjet media can provide difficulties when stacking, aligning, and/or finishing. For example, the partially dried inkjet media can have distorted properties such as a curl, a cockle, a reduction in stiffness, increased surface roughness, extruding fibers from the surface, misaligned fibers, and/or increased sheet to sheet friction of the media. In some examples, these distorted properties can be

caused by printing fluid deposited on the media and the media absorbing the printing fluid. For example, the printing fluid can be in a liquid state that can be absorbed by a media such as paper. In this example, the liquid state of the printing fluid can cause the distorted properties of the media in a similar way that other liquids may distort the properties of the media.

In some examples, the partially dried inkjet media conditioner can include a heated pressure roller within a print engine of the printing device. As used herein, a print engine encases (e.g., cover within an area, dispose within an area, fix within an area, etc.) a print zone within the printing device. In some examples, the print zone includes an area within the print engine to deposit printing fluid on a print media (e.g., paper, plastic, etc.). In some examples, the heated pressure roller can be utilized to increase evaporation of the printing fluid and/or increase drying of the partially dried inkjet media. In some examples, the increased evaporation of printing fluid can result in an increase of moisture, steam, and/or vapor within the print engine. In some examples, the partially dried inkjet media conditioner can be coupled to a vapor manager to remove moisture, steam, and/or vapor from an output of the partially dried inkjet media conditioner.

The figures herein follow a numbering convention in which the first digit corresponds to the drawing figure number and the remaining digits identify an element or component in the drawing. Elements shown in the various figures herein may be capable of being added, exchanged, and/or eliminated so as to provide a number of additional examples of the present disclosure. In addition, the proportion and the relative scale of the elements provided in the figures are intended to illustrate the examples of the present disclosure, and should not be taken in a limiting sense.

FIG. 1 illustrates an example system 100 for a partially dried inkjet media conditioner consistent with the present disclosure. In some examples, the system 100 can include a print engine 102 that includes a print zone 104. In some examples, the print engine 102 can encase the print zone 104. As used herein, a print engine 102 includes a plurality of components for generating an image on print media within a housing. The housing of the print engine can physically encase the plurality of components (e.g., provide a physical barrier for the plurality of components within the print engine). In some examples, the plurality of components can include, but are not limited to: print heads, printing fluid supply, electronics, drivers, print zone, media pathways, image processing devices, and/or computing devices.

As used herein, the print zone 104 is an area that deposits a printing fluid on to a print media. In some examples, the print media can be directed out of the print zone 104 as partially dried inkjet media. In some examples, the partially dried inkjet media can be provided to a conditioner 108 by a media pathway 106. In some examples, the conditioner 108 can include a heated pressure roller. In some examples, the conditioner 108 can also include additional elements that promote conditioning of the partially dried inkjet media. For example, the conditioner 108 can include a vapor manager, input and output rollers to transition the partially dried inkjet media from a first direction to a second direction, and/or other elements to remove distorted properties of the partially dried inkjet media.

In some examples, the conditioner 108 can include a pressure roller to receive a first side of the partially dried inkjet media from the print zone 104. In some examples, the pressure roller can be positioned to receive a top side of the partially dried inkjet media as illustrated in FIG. 1. For

examples, the pressure roller of the conditioner 108 can be positioned above a heated roller as illustrated in FIG. 1 to interact with a top side of the partially dried inkjet media. In some examples, the heated roller can be a belt roller as described herein.

In some examples, the conditioner 108 can include a heated roller to receive a second side of the partially dried inkjet media from the print zone 104. In some examples, the second side of the partially dried inkjet media can be an opposite side from the first side of the partially dried inkjet media. In some examples, the heated roller can be positioned below a pressure roller as described herein. In some examples, the heated roller can be utilized to apply heat to the second side of the partially dried inkjet media.

In some examples, the conditioner 108 can be encased within the print engine as described herein. In some examples, the conditioner 108 can increase evaporation of printing fluid applied to the partially dried inkjet media and/or increase drying of the partially dried inkjet media. In some examples, the conditioner 108 can generate moisture, steam, and/or vapor within the print engine 102 from the increased evaporation of the partially dried inkjet media. In some examples, the system 100 can include a vapor manager at an output of the conditioner 108 to remove the moisture, steam, and/or vapor from within the print engine 102.

As described herein, the partially dried inkjet media can provide difficulties when stacking, aligning, and/or finishing. By including a conditioner 108 within the print engine 102, the partially dried inkjet media can be dried at a relatively faster rate without increasing a foot print of the system 100. In addition, including the conditioner 108 within the print engine 102 can allow standard devices (e.g., paper handling accessories, etc.) to be coupled to an output of the system 100. For example, an output of the print engine 102 can be mated with a standard device without modification of the output and/or the standard device.

FIG. 2 illustrates an example system 200 for a partially dried inkjet media conditioner consistent with the present disclosure. In some examples, the system 200 can include a number of features that are the same or similar as system 100 as referenced in FIG. 1. For example, the system 200 can include a print engine 202 that encases a print zone 204. In some examples, the system 200 can be an inkjet printing device with an inkjet print zone 204. As described herein, the print zone 204 can include a plurality of inkjets to deposit printing fluid on to print media.

In some examples, the print zone 204 can receive print media from a print media storage 218 (e.g., media tray, paper tray, etc.). In some examples, the print zone 204 can be coupled to the print media storage 218 by a media pathway. In some examples, the print zone 204 can be coupled to an input 210-1 of a dryer zone 210. In some examples, the dryer zone 210 can be a media pathway to allow the partially dried inkjet media from the print zone 204 to dry while the partially dried inkjet media is within the dryer zone 210. In some examples, the dryer zone 210 can include air circulation, heating devices, and/or other drying elements to increase drying of the partially dried inkjet media.

In some examples, the dryer zone 210 can be coupled to a media pathway 206 to direct the partially dried inkjet media to a conditioner 208. In some examples, the dryer zone 210 can be coupled to the media pathway 206 at position 209. In some examples, the position 209 can be between an input 210-1 of the dryer zone 210 and an output 210-2 of the dryer zone 210. That is, when the partially dried inkjet media is directed to the conditioner 208, the partially dried inkjet media may not pass through the output 210-2 of

the dryer zone 210. For example, the partially dried inkjet media may pass through a first portion of the dryer zone 210 and bypass a second portion of the dryer zone 210. In some examples, the first portion of the dryer zone 210 can be approximately 70 percent of the total dryer zone 210 and the second portion of the dryer zone 210 can be approximately 30 percent of the total dryer zone 210.

In some examples, the system 200 can utilize a portion of the dryer zone 210. In some examples, a speed of the 10 partially dried inkjet media can be reduced to increase a quantity of time the partially dried inkjet media is within the dryer zone 210. In some examples, the temperature of the dryer zone 210 can be increased to provide a similar drying effect as if the partially dried inkjet media passed through the 15 entire dryer zone 210.

In some examples, the output 210-2 of the dryer zone 210 can be coupled to a duplexer zone 212. In some examples, the duplexer zone 212 can be utilized for duplexing relatively large print media (e.g., longer media such as Legal, 20 A3, B size, etc.). In some examples, the duplexer zone 212 can be utilized to bypass the conditioner 208 until the relatively large print media has been returned to the print zone 204 to deposit printing fluid on a second side of the relatively large print media. For example, print media from 25 the print media storage 218 can be provided to the print zone 204. In this example, the print zone 204 can deposit printing fluid to a first side of the print media. In this example, the print media can be partially dried inkjet media provided to the input 210-1 of the dryer zone 210. In this example, the 30 partially dried inkjet media can be relatively large partially dried inkjet media that is provided to the duplexer zone 212 and returned to the print zone 204 to deposit printing fluid on a second side of the print media. In some examples, the relatively large partially dried inkjet media that is designated 35 for single sided printing can be provided to the input 210-1 of the dryer zone 210 and provided to the conditioner 208 as described herein.

In some examples, the conditioner 208 can include a heated pressure roller. In some examples, the conditioner 40 208 can include a single direction heated pressure roller. In some examples, the conditioner 208 can include a single direction heated pressure roller to avoid conditioning a first portion of the partially dried inkjet media without conditioning a second portion, which can cause inconsistent sheet characteristics. For example, the conditioner 208 can receive the partially dried inkjet media at an input and provide the partially dried inkjet media to an acceleration zone 214. In this example, the conditioner 208 may not be able to reverse the direction of the partially dried inkjet media. For example, the conditioner 208 can receive partially dried inkjet media from the media pathway 206 and provide the partially dried inkjet media to the acceleration zone 214, but may not be able to reverse the direction of the partially dried inkjet media to provide the partially dried inkjet media from the acceleration zone 214 to the media pathway 206. This example can reduce cost of including a multi-directional heated pressure roller. This example can also prevent generated moisture, steam, and/or vapor generated by the heated pressure roller from exiting at the input of the conditioner 208. In some examples, the acceleration zone 214 can be utilized to provide the partially dried inkjet media to the output zone 216 at an accelerated rate to provide a greater quantity of time for paper handling accessories to process each sheet of partially dried inkjet media.

In some examples, the media pathway 206 can include a 60 vertical portion (e.g., upward direction as illustrated in FIG. 2) that is coupled to the dryer zone 210 at position 209. In

some examples, the vertical portion can bring the partially dried inkjet media from the dryer zone to a transition point 250. In some examples, the transition point 250 can direct the partially dried inkjet media from the vertical portion to a horizontal portion (e.g., directed from the left side of the print engine 202 to a right side of the print engine 202 as illustrated in FIG. 2). In some examples, the horizontal portion of the media pathway 206 can be coupled to the conditioner 208.

In some examples, the acceleration zone 214 can be utilized to increase a rate of the partially dried inkjet media for providing the partially dried inkjet media to an output zone 216. In some examples, the acceleration zone 214 can include a plurality of rollers to accelerate the rate or speed of the partially dried inkjet media. In some examples, the output zone 216 can be positioned above the print zone 204 on a right side of the print engine 202 as illustrated in FIG. 2. In some examples, the output zone 216 can be positioned on an opposite side of the print engine 202 than the conditioner 208. In some examples, positioning the conditioner 208 on a first side of the print engine 202 and positioning the output zone 216 on a second side of the print engine 202 can increase a distance of the acceleration zone 214.

In some examples, the conditioner 208 can include a heated pressure roller. In some examples, the heated pressure roller can be encased within the print engine 202 as described herein. In some examples, the heated pressure roller can include a pressure roller 208-1 to receive a first side of the partially dried inkjet media from the media pathway 206. In some examples, the pressure roller 208-1 can apply pressure to the first side of the partially dried inkjet media. In some examples, the increased pressure can increase evaporation of the printing fluid applied to the partially dried inkjet media. The increased evaporation of the printing fluid can increase drying of the partially dried inkjet media, which can restore a number of distorted properties of the partially dried inkjet media.

In some examples, the increased evaporation of the printing fluid can increase moisture, steam, and/or vapor at an output of the conditioner 208 or within the acceleration zone 214. In some examples, the increased moisture, steam, and/or vapor can result in condensation within the print engine 202 and can damage the partially dried inkjet media and/or components within the print engine 202. In some examples, a vapor manager can be coupled to an output of the conditioner 208. For example, a vapor manager can be coupled between the conditioner 208 and the acceleration zone 214. In some examples, the vapor manager can include an exhaust fan to remove moisture, steam, and/or vapor from the output of the conditioner 208.

In some examples, the conditioner 208 can include a heated pressure roller that is aligned in a vertical orientation. As used herein, a heated pressure roller in a vertical orientation includes a pressure roller 208-1 that is positioned above a heated roller 208-2. In some examples, the vertical orientation includes a center of a pressure roller 208-1 aligned vertically above a center of a heated roller 208-2.

In some examples, the conditioner 208 can be a removable conditioner. For example, the conditioner 208 can be removed from the print engine 202. In some examples, the conditioner 208 can include an enclosure that can be removed from an opening on a left side of the print engine 202 as illustrated in FIG. 2. In some examples, the conditioner 208 can be removed through an opening on a front side of the print engine 202 as illustrated in FIG. 2. For example, the conditioner 208 can be pulled out of the front of the print engine 202.

In some examples, the conditioner 208 can be positioned on an upper left portion of the print engine 202 as illustrated in FIG. 2. In these examples, the conditioner 208 can be positioned above dryer zone 210. In some examples, the conditioner 208 can be positioned directly above the dryer zone 210. In some examples, the conditioner 208 can be positioned in a first corner of the print engine 202 and the print zone 204 can be positioned in a second corner of the print engine 202. In some examples, positioning the conditioner 208 above the print zone 204 and above the dryer zone 210 can allow the moisture, steam, and/or vapor to be removed out of the side and/or top of the print engine 202.

As described herein, the partially dried inkjet media can provide difficulties when stacking, aligning, and/or finishing. By including a conditioner 208 within the print engine 202, the partially dried inkjet media can be dried at a relatively faster rate without increasing a footprint of the system 200. In addition, including the conditioner 208 within the print engine 202 can allow standard devices (e.g., paper handling accessories, etc.) to be coupled to an output 216 of the system 200.

FIG. 3 illustrates an example system for a partially dried inkjet media conditioner consistent with the present disclosure. In some examples, the system 300 can include a number of features that are the same or similar as system 100 as referenced in FIG. 1 and/or system 200 as referenced in FIG. 2. For example, the system 300 can include a print engine 302 that encases a print zone 304. In some examples, the system 300 can be an inkjet printing device with an inkjet print zone 304. As described herein, the print zone 304 can include a plurality of inkjets to deposit printing fluid on print media.

In some examples, the print zone 304 can receive print media from a print media storage 318. In some examples, the print zone 304 can be coupled to the print media storage 318 by a media pathway. In some examples, the print zone 304 can be coupled to an input 310-1 of a dryer zone 310. In some examples, the dryer zone 310 can be a media pathway to allow the partially dried inkjet media from the print zone 304 to dry while the partially dried inkjet media is within the dryer zone 310. In some examples, the dryer zone 310 can include air circulation, heat sources, and/or other drying elements to increase drying of the partially dried inkjet media.

In some examples, the dryer zone 310 can be coupled to a media pathway 306 to direct the partially dried inkjet media to a conditioner 308. In some examples, the dryer zone 310 can be coupled to the media pathway 306 at position 309. In some examples, the position 309 can be between an input 310-1 of the dryer zone 310 and an output 310-2 of the dryer zone 310. That is, when the partially dried inkjet media is directed to the conditioner 308, the partially dried inkjet media may not pass through the output 310-2 of the dryer zone 310. For example, the partially dried inkjet media may pass through a first portion of the dryer zone 310 and bypass a second portion of the dryer zone 310.

In some examples, the system 300 can utilize a portion of the dryer zone 310. In some examples, a speed of the partially dried inkjet media can be reduced to increase a quantity of time the partially dried inkjet media is within the portion of the dryer zone 310. In some examples, the temperature of the dryer zone 310 can be increased to provide a similar drying effect as if the partially dried inkjet media passed through the entire dryer zone 310.

In some examples, the output 310-2 of the dryer zone 310 can be coupled to a duplex zone 312. In some examples, the duplex zone 312 can be utilized for duplexing rela-

tively large print media (e.g., longer media such as Legal, A3, B size, etc.). In some examples, the duplexer zone 312 can be utilized to bypass the conditioner 308 until the relatively large print media has been returned to the print zone 304 to deposit printing fluid on a second side of the relatively large print media.

In some examples, the conditioner 308 can include a heated pressure roller. In some examples, the conditioner 308 can be a single direction heated pressure roller. For example, the conditioner 308 can receive the partially dried inkjet media at an input and provide the partially dried inkjet media to an acceleration zone 314. In this example, the conditioner 308 may not be able to reverse the direction of the partially dried inkjet media. For example, the conditioner 308 can receive partially dried inkjet media from the media pathway 306 and provide the partially dried inkjet media to the acceleration zone 314, but may not be able to reverse the direction of the partially dried inkjet media to provide the partially dried inkjet media from the acceleration zone 314 to the media pathway 306. This example can reduce cost of including a multi-directional heated pressure roller. This example can also prevent generated moisture, steam, and/or vapor generated by the heated pressure roller from exiting at the input of the conditioner 308. In some examples, the acceleration zone 314 can be utilized to provide the partially dried inkjet media to the output zone 316 at an accelerated rate to provide a greater quantity of time for paper handling accessories to process each sheet of partially dried inkjet media.

In some examples, the media pathway 306 can include a vertical portion (e.g., upward direction as illustrated in FIG. 3) that is coupled to the dryer zone 310 at position 309. In some examples, the vertical portion can bring the partially dried inkjet media from the dryer zone to the conditioner 308. In some examples, a transition point may not be utilized with a conditioner 308 when the conditioner 308 is in an angled orientation as described further herein.

In some examples, the conditioner 308 can include a heated pressure roller. In some examples, the heated pressure roller can be encased within the print engine 302 as described herein. In some examples, the heated pressure roller can include a pressure roller 308-1 to receive a first side of the partially dried inkjet media from the media pathway 306. In some examples, the pressure roller 308-1 can apply pressure to the first side of the partially dried inkjet media. In some examples, the heated pressure roller can include a heated roller 308-2 to apply heat to a second side of the partially dried inkjet media. In some examples, the increased pressure and heat can increase evaporation of the printing fluid applied to the partially dried inkjet media. The increased evaporation of the printing fluid can increase drying of the partially dried inkjet media, which can restore a number of distorted properties of the partially dried inkjet media.

In some examples, the conditioner 308 can include a heated pressure roller that is aligned in an angled orientation. As used herein, a heated pressure roller in an angled orientation includes a pressure roller 308-1 that is positioned at an angle above a heated roller 308-2. In some examples, the angled orientation includes a center of a pressure roller 208-1 aligned to the left and above a center of a heated roller 308-2 as illustrated in FIG. 3. In some examples, the angled orientation can be utilized without a horizontal portion of the media pathway 308. For example, the media pathway 308 can be substantially vertical from the dryer zone 310 to the conditioner 308.

In some examples, the increased evaporation of the printing fluid can increase moisture, steam, and/or vapor at an output of the conditioner 308 or within the acceleration zone 314. In some examples, the increased moisture, steam, and/or vapor can result in condensation within the print engine 302 and can damage the partially dried inkjet media and/or components within the print engine 302. In some examples, a vapor manager can be coupled to an output of the conditioner 308. For example, a vapor manager can be coupled between the conditioner 308 and the acceleration zone 314. In some examples, the vapor manager can include an exhaust fan to remove moisture, steam, and/or vapor from the output of the conditioner 308.

In some examples, the conditioner 308 can be a removable conditioner. For example, the conditioner 308 can be removed from the print engine 302. In some examples, the conditioner 308 can include an enclosure that can be removed from an opening on a left side of the print engine 302 as illustrated in FIG. 3. In some examples, the conditioner 308 can be removed through an opening on a front side of the print engine 302 as illustrated in FIG. 3. For example, the conditioner 308 can be pulled out of the front of the print engine 302.

In some examples, the conditioner 308 can be positioned on an upper left portion of the print engine 302 as illustrated in FIG. 3. In some examples, the angled orientation of the conditioner 308 can allow the conditioner 308 to be positioned closer to the left side of the print engine 302 as illustrated in FIG. 3 compared to a vertical orientation. In some examples, the angled orientation can provide a relatively shorter travel distance for removal of the conditioner 308. In these examples, the conditioner 308 can be positioned above dryer zone 310. In some examples, the conditioner 308 can be positioned directly above the dryer zone 310. In some examples, the conditioner 308 can be positioned in a first corner of the print engine 302 and the print zone 304 can be positioned in a second corner of the print engine 302. In some examples, positioning the conditioner 308 above the print zone 304 and above the dryer zone 310 can allow the moisture, steam, and/or vapor to be removed out of the side or top of the print engine 302.

As described herein, the partially dried inkjet media can provide difficulties when stacking, aligning, and/or finishing. By including a conditioner 308 within the print engine 302, the partially dried inkjet media can be dried at a relatively faster rate without increasing a foot print of the system 300. In addition, including the conditioner 308 within the print engine 302 can allow standard devices (e.g., paper handling accessories, etc.) to be coupled to an output 316 of the system 300.

FIG. 4 illustrates an example system 400 for a partially dried inkjet media conditioner consistent with the present disclosure. In some examples, the system 400 can include a number of features that are the same or similar as system 100 as referenced in FIG. 1, system 200 as referenced in FIG. 2, and/or system 300 as referenced in FIG. 3. For example, the system 400 can include a print engine 402 that encases a print zone 404, a dryer zone 410 with an input 410-1 coupled to the print zone 404 and an output 410-2 coupled to a conditioner 408.

As described herein, the conditioner 408 can include a heated pressure roller that includes a pressure roller 408-1 to receive a first side of partially dried inkjet media and a heated roller 408-2 to receive a second side of partially dried inkjet media. In some examples, the heated pressure roller of the conditioner 408 can be coupled to an output 410-2 of the dryer zone 410. In these examples, the partially dried inkjet

media is able to pass through the entire dryer zone 410 when provided to the conditioner 408.

In some examples, the system 400 can include a duplexer zone 412. In some examples, the duplexer zone 412 can be utilized for duplexing relatively large print media (e.g., longer media such as Legal, A3, B size, etc.). In some examples, the duplexer zone 412 can be utilized to bypass the conditioner 408 until the relatively large print media has been returned to the print zone 404 to deposit printing fluid on a second side of the relatively large print media. In some examples, the duplexer zone 412 can be positioned above the dryer zone 410 and/or the conditioner 408. In some examples, the duplexer zone 412 can be coupled to a position 409 of the dryer zone 410. In some examples, the position 409 of the dryer zone 410 can be between an input 410-1 and an output 410-2 of the dryer zone 410.

In some examples, the conditioner 408 can be positioned in line with an output 416 of the print engine 402. For example, the output of the conditioner 408 can be coupled to an acceleration zone 414 that can provide the partially dried inkjet media to the output 416 of the print engine 402 substantially horizontal. The acceleration zone 414 can increase the speed of the partially dried inkjet media by positioning the conditioner in line with the output 416 of the print engine 402.

In some examples, the conditioner 408 can include a heated pressure roller that is aligned in a vertical orientation. As used herein, a heated pressure roller in a vertical orientation includes a pressure roller 408-1 that is positioned above a heated roller 408-2. In some examples, the vertical orientation includes a center of a pressure roller 408-1 aligned vertically above a center of a heated roller 408-2. In some examples, the conditioner 408 can be removed through an opening on a front side of the print engine 402 as illustrated in FIG. 4. For example, the conditioner 408 can be pulled out of the front of the print engine 402.

In some examples, the conditioner 408 can increase evaporation of printing fluid deposited on the partially dried inkjet media. In some examples, the increased evaporation of the printing fluid can increase moisture, steam, and/or vapor at an output of the conditioner 408 or within the acceleration zone 414. In some examples, the increased moisture, steam, and/or vapor can result in condensation within the print engine 402 and can damage the partially dried inkjet media and/or components within the print engine 402. In some examples, a vapor manager can be coupled to an output of the conditioner 408. For example, a vapor manager can be coupled between the conditioner 408 and the acceleration zone 414. In some examples, the vapor manager can include an exhaust fan to remove moisture, steam, and/or vapor from the output of the conditioner 408.

As described herein, the partially dried inkjet media can provide difficulties when stacking, aligning, and/or finishing. By including a conditioner 408 within the print engine 402, the partially dried inkjet media can be dried at a relatively faster rate without increasing a foot print of the system 400. In addition, including the conditioner 408 within the print engine 402 can allow standard devices (e.g., paper handling accessories, etc.) to be coupled to an output 416 of the system 400.

FIG. 5 illustrates an example system 500 for a partially dried inkjet media conditioner consistent with the present disclosure. In some examples, the system 500 can include a number of features that are the same or similar as system 100 as referenced in FIG. 1, system 200 as referenced in FIG. 2, system 300 as referenced in FIG. 3, and/or system 400 as referenced in FIG. 4. For example, the system 500 can

include a print engine 502 that encases a print zone 504, a dryer zone 510 with an input 510-1 coupled to the print zone 504 and an output 510-2 coupled to a conditioner 508.

As described herein, the conditioner 508 can include a heated pressure roller that includes a pressure roller 508-1 to receive a first side of partially dried inkjet media and a heated roller 508-2 to receive a second side of partially dried inkjet media. In some examples, the heated pressure roller of the conditioner 508 can be coupled to an output 510-2 of the dryer zone 510 by a media path 550-1. In these examples, the partially dried inkjet media is able to pass through the entire dryer zone 510.

In some examples, the media path 550-1 can direct the partially dried inkjet media in an upward vertical direction and in a horizontal direction prior to providing the partially dried inkjet media to the conditioner 508. In these examples, the output 510-2 of the dryer zone 510 can be in line with an output 516 of the print engine 502. In these examples, the conditioner 508 can be positioned above the output 510-2 of the dryer zone 510 and/or an output 516 of the print engine 502. In some examples, the output of the conditioner 508 can be coupled to an acceleration zone 514 by a media path 550-2. In some examples, the media path 550-2 can vertically lower the partially dried inkjet media from the output of the conditioner 508 to an input of the acceleration zone 514.

In some examples, the system 500 can include a duplexer zone 512. In some examples, the duplexer zone 512 can be utilized for duplexing relatively large print media (e.g., longer media such as Legal, A3, B size, etc.). In some examples, the duplexer zone 512 can be utilized to bypass the conditioner 508 until the relatively large print media has been returned to the print zone 504 to deposit printing fluid on a second side of the relatively large print media. In some examples, the duplexer zone 512 can be positioned inline with the dryer zone 510 and/or below the conditioner 508. In some examples, the duplexer zone 512 can be coupled to an output 510-2 of the dryer zone 510.

In some examples, the conditioner 508 can be positioned above the print zone 504 and the duplexer zone 512. In some examples, the conditioner 508 can include a heated pressure roller that is aligned in a vertical orientation. As used herein, a heated pressure roller in a vertical orientation includes a pressure roller 508-1 that is positioned above a heated roller 508-2. In some examples, the vertical orientation includes a center of a pressure roller 508-1 aligned vertically above a center of a heated roller 508-2. In some examples, the conditioner 508 can be removed through an opening on a front side of the print engine 502 as illustrated in FIG. 5. For example, the conditioner 508 can be pulled out of the front of the print engine 502.

In some examples, the conditioner 508 can increase evaporation of printing fluid deposited on the partially dried inkjet media. In some examples, the increased evaporation of the printing fluid can increase moisture, steam, and/or vapor at an output of the conditioner 508 or within the acceleration zone 514. In some examples, the increased moisture, steam, and/or vapor can result in condensation within the print engine 502 and can damage the partially dried inkjet media and/or components within the print engine 502. In some examples, a vapor manager can be coupled to an output of the conditioner 508. For example, a vapor manager can be coupled between the conditioner 508 and the acceleration zone 514. In some examples, the vapor manager can include an exhaust fan to remove moisture, steam, and/or vapor from the output of the conditioner 508.

As described herein, the partially dried inkjet media can provide difficulties when stacking, aligning, and/or finishing. By including a conditioner **508** within the print engine **502**, the partially dried inkjet media can be dried at a relatively faster rate without increasing a foot print of the system **500**. In addition, including the conditioner **508** within the print engine **502** can allow standard devices (e.g., paper handling accessories, etc.) to be coupled to an output **516** of the system **500**.

FIG. 6 illustrates an example system for a partially dried inkjet media conditioner consistent with the present disclosure. In some examples, the system **600** can include a number of features that are the same or similar as system **100** as referenced in FIG. 1, system **200** as referenced in FIG. 2, system **300** as referenced in FIG. 3, system **400** as referenced in FIG. 4, and/or system **500** as referenced in FIG. 5. For example, the system **600** can include a print engine **602** that encases a print zone **604**, a dryer zone **610** with an input **610-1** coupled to the print zone **604** and an output **610-2** coupled to a conditioner **608**.

As described herein, the conditioner **608** can include a heated pressure roller that includes a pressure roller **608-1** to receive a first side of partially dried inkjet media and a heated roller **608-2** to receive a second side of partially dried inkjet media. In some examples, the heated pressure roller of the conditioner **608** can be utilized to increase evaporation of printing fluid applied to the partially dried inkjet media from the print zone **604**. In some examples, the heated pressure roller of the conditioner **608** can be coupled to an output **610-2** of the dryer zone **610** by a media path **650-1**. In these examples, the partially dried inkjet media is able to pass through the entire dryer zone **610**.

In some examples, the media path **650-1** can direct the partially dried inkjet media in an upward vertical direction to provide the partially dried inkjet media to the conditioner **608**. In these examples, the output **610-2** of the dryer zone **610** can be in line with an output **616** of the print engine **602**. In these examples, the conditioner **608** can be positioned above the output **610-2** of the dryer zone **610** and/or an output **616** of the print engine **602**. In some examples, the output of the conditioner **608** can be coupled to an acceleration zone **614** by media paths **650-2**, **650-3**, **650-4**. In some examples, the media path **650-2** can horizontally move the partially dried inkjet media from the output of the conditioner **608** to media path **650-3**. In some examples, the media path **650-3** can vertically lower the partially dried inkjet media to media path **650-4**. In some examples, the media path **650-4** can horizontally direct the partially dried inkjet media to an input of the acceleration zone **614**.

In some examples, the system **600** can include a duplexer zone **612**. In some examples, the duplexer zone **612** can be utilized for duplexing relatively large print media (e.g., longer media such as Legal, A3, B size, etc.). In some examples, the duplexer zone **612** can be utilized to bypass the conditioner **608** until the relatively large print media has been returned to the print zone **604** to deposit printing fluid on a second side of the relatively large print media. In some examples, the duplexer zone **612** can be positioned inline with the dryer zone **610** and/or below the conditioner **608**. In some examples, the duplexer zone **612** can be coupled to an output **610-2** of the dryer zone **610**.

In some examples, the conditioner **608** can be positioned above the print zone **604** and the duplexer zone **612**. In some examples, the conditioner **608** can include a heated pressure roller that is aligned in a horizontal orientation. As used herein, a heated pressure roller in a horizontal orientation includes a pressure roller **608-1** that is positioned on a first

side (e.g., left side as illustrated in FIG. 6) and a heated roller **608-2** positioned on a second side (e.g., right side as illustrated in FIG. 6). In some examples, the horizontal orientation includes a center of a pressure roller **608-1** aligned horizontal side by side with a center of a heated roller **608-2**. In some examples, the conditioner **608** can include an enclosure that can be removed from an opening on a left side of the print engine **602** as illustrated in FIG. 6. In some examples, the conditioner **608** can be removed through an opening on a front side of the print engine **602** as illustrated in FIG. 6. For example, the conditioner **608** can be pulled out of the front of the print engine **602**.

In some examples, the conditioner **608** can increase evaporation of printing fluid deposited on the partially dried inkjet media. In some examples, the increased evaporation of the printing fluid can increase moisture, steam, and/or vapor at an output of the conditioner **608** or within the acceleration zone **614**. In some examples, the increased moisture, steam, and/or vapor can result in condensation within the print engine **602** and can damage the partially dried inkjet media and/or components within the print engine **602**. In some examples, a vapor manager can be coupled to an output of the conditioner **608**. For example, a vapor manager can be coupled between the conditioner **608** and the acceleration zone **614**. In some examples, the vapor manager can include an exhaust fan to remove moisture, steam, and/or vapor from the output of the conditioner **608**.

As described herein, the partially dried inkjet media can provide difficulties when stacking, aligning, and/or finishing. By including a conditioner **608** within the print engine **602**, the partially dried inkjet media can be dried at a relatively faster rate without increasing a foot print of the system **600**. In addition, including the conditioner **608** within the print engine **602** can allow standard devices (e.g., paper handling accessories, etc.) to be coupled to an output **616** of the system **600**.

FIG. 7 illustrates an example system **700** for a partially dried inkjet media conditioner consistent with the present disclosure. In some examples, the system **700** can include a number of features that are the same or similar as system **100** as referenced in FIG. 1, system **200** as referenced in FIG. 2, system **300** as referenced in FIG. 3, system **400** as referenced in FIG. 4, system **500** as referenced in FIG. 5, and/or system **600** as referenced in FIG. 6. For example, the system **700** can include a print engine **702** that encases a print zone **704**, a dryer zone **710** with an input **710-1** coupled to the print zone **704** and an output **710-2** coupled to a conditioner **708**.

As described herein, the conditioner **708** can include a heated pressure roller that includes a pressure roller **708-1** to receive a first side of partially dried inkjet media and a heated roller **708-2** to receive a second side of partially dried inkjet media. In some examples, the heated pressure roller of the conditioner **708** can be coupled to an output **710-2** of the dryer zone **710** by a media path **750-1**. In these examples, the partially dried inkjet media is able to pass through the entire dryer zone **710**.

In some examples, the media path **750-1** can direct the partially dried inkjet media in an upward vertical direction and in a horizontal direction prior to providing the partially dried inkjet media to the conditioner **708**. In these examples, the output **710-2** of the dryer zone **710** can be in line with an output **716** of the print engine **702**. In these examples, the conditioner **708** can be positioned above the output **710-2** of the dryer zone **710** and/or an output **716** of the print engine **702**. In some examples, the output of the conditioner **708** can be coupled to an acceleration zone **714** by media paths

750-2, 750-3. In some examples, the media path **750-2** can vertically lower the partially dried inkjet media and direct the partially dried inkjet media away from the output **716** of the print engine **702** prior to providing the partially dried inkjet media to media path **750-3**. In some examples, media path **750-3** can vertically lower and provide the partially dried inkjet media to an input of the acceleration zone **714**. In some examples, the media paths **750-2, 750-3** can increase a length of the acceleration zone **714**.

In some examples, the system **700** can include a duplexer zone **712**. In some examples, the duplexer zone **712** can be utilized for duplexing relatively large print media (e.g., longer media such as Legal, A3, B size, etc.). In some examples, the duplexer zone **712** can be utilized to bypass the conditioner **708** until the relatively large print media has been returned to the print zone **704** to deposit printing fluid on a second side of the relatively large print media. In some examples, the duplexer zone **712** can be positioned inline with the dryer zone **710** and/or below the conditioner **708**. In some examples, the duplexer zone **712** can be coupled to an output **710-2** of the dryer zone **710**.

In some examples, the conditioner **708** can be positioned above the print zone **704** and the duplexer zone **712**. In some examples, the conditioner **708** can include a heated pressure roller that is aligned in a vertical orientation. As used herein, a heated pressure roller in a vertical orientation includes a pressure roller **708-1** that is positioned above a heated roller **708-2**. In some examples, the vertical orientation includes a center of a pressure roller **708-1** aligned vertically above a center of a heated roller **708-2**. In some examples, the conditioner **708** can be removed through an opening on a front side of the print engine **702** as illustrated in FIG. 7. For example, the conditioner **708** can be pulled out of the front of the print engine **702**.

In some examples, the conditioner **708** can increase evaporation of printing fluid deposited on the partially dried inkjet media. In some examples, the increased evaporation of the printing fluid can increase moisture, steam, and/or vapor at an output of the conditioner **708** or within the acceleration zone **714**. In some examples, the increased moisture, steam, and/or vapor can result in condensation within the print engine **702** and can damage the partially dried inkjet media and/or components within the print engine **702**. In some examples, a vapor manager can be coupled to an output of the conditioner **708**. For example, a vapor manager can be coupled between the conditioner **708** and the acceleration zone **714**. In some examples, the vapor manager can include an exhaust fan to remove moisture, steam, and/or vapor from the output of the conditioner **708**.

As described herein, the partially dried inkjet media can provide difficulties when stacking, aligning, and/or finishing. By including a conditioner **708** within the print engine **702**, the partially dried inkjet media can be dried at a relatively faster rate without increasing a foot print of the system **700**. In addition, including the conditioner **708** within the print engine **702** can allow standard devices (e.g., paper handling accessories, etc.) to be coupled to an output **716** of the system **700**.

FIG. 8 illustrates an example system for a partially dried inkjet media conditioner consistent with the present disclosure. In some examples, the system **800** can include a number of features that are the same or similar as system **100** as referenced in FIG. 1, system **200** as referenced in FIG. 2, system **300** as referenced in FIG. 3, system **400** as referenced in FIG. 4, system **500** as referenced in FIG. 5, **600** as referenced in FIG. 6 and/or system **700** as referenced in FIG. 7. For example, the system **800** can include a print engine

802 that encases a print zone **804**, a dryer zone **810** with an input **810-1** coupled to the print zone **804** and an output **810-2** coupled to a conditioner **808**.

As described herein, the conditioner **808** can include a heated pressure roller that includes a pressure roller **808-1** to receive a first side of partially dried inkjet media and a heated roller **808-2** to receive a second side of partially dried inkjet media. In some examples, the heated pressure roller of the conditioner **808** can be coupled to an output **810-2** of the dryer zone **810** by media paths **850-1, 850-2**. In these examples, the partially dried inkjet media is able to pass through the entire dryer zone **810**. In these examples, the conditioner **808** can be positioned in an upper left corner of the print engine **802** as illustrated in FIG. 8. In some examples, utilizing the media paths **850-1, 850-2** can increase a length of an acceleration path **814**.

In some examples, the media path **850-1** can direct the partially dried inkjet media in an upward vertical direction and in a horizontal direction away from an output **816** of the print engine **802** prior to providing the partially dried inkjet media to the conditioner **808**. In these examples, the output **810-2** of the dryer zone **810** can be in line with an output **816** of the print engine **802**. In these examples, the conditioner **808** can be positioned above the output **810-2** of the dryer zone **810** and/or an output **816** of the print engine **802**. In some examples, the conditioner can be positioned directly above the dryer zone **810** and/or in an opposite corner of the print engine than the print zone **804**. In some examples, the output of the conditioner **808** can be coupled to an acceleration zone **814**.

In some examples, the system **800** can include a duplexer zone **812**. In some examples, the duplexer zone **812** can be utilized for duplexing relatively large print media (e.g., longer media such as Legal, A3, B size, etc.). In some examples, the duplexer zone **812** can be utilized to bypass the conditioner **808** until the relatively large print media has been returned to the print zone **804** to deposit printing fluid on a second side of the relatively large print media. In some examples, the duplexer zone **812** can be positioned inline with the dryer zone **810** and/or below the conditioner **808**. In some examples, the system **800** can utilize media paths **850-1, 850-2** as a duplexer zone. In some examples, the duplexer zone **812** can be coupled to an output **810-2** of the dryer zone **810**.

In some examples, the conditioner **808** can be positioned above the print zone **804** and the dryer zone **810**. In some examples, the conditioner **808** can include a heated pressure roller that is aligned in a vertical orientation. As used herein, a heated pressure roller in a vertical orientation includes a pressure roller **808-1** that is positioned above a heated roller **808-2**. In some examples, the vertical orientation includes a center of a pressure roller **808-1** aligned vertically above a center of a heated roller **808-2**. In some examples, the conditioner **808** can include an enclosure that can be removed from an opening on a left side of the print engine **802** as illustrated in FIG. 8. In some examples, the conditioner **808** can be removed through an opening on a front side of the print engine **802** as illustrated in FIG. 8.

In some examples, the conditioner **808** can increase evaporation of printing fluid deposited on the partially dried inkjet media. In some examples, the increased evaporation of the printing fluid can increase moisture, steam, and/or vapor at an output of the conditioner **808** or within the acceleration zone **814**. In some examples, the increased moisture, steam, and/or vapor can result in condensation within the print engine **802** and can damage the partially dried inkjet media and/or components within the print

15

engine 802. In some examples, a vapor manager can be coupled to an output of the conditioner 808. For example, a vapor manager can be coupled between the conditioner 808 and the acceleration zone 814. In some examples, the vapor manager can include an exhaust fan to remove moisture, steam, and/or vapor from the output of the conditioner 808.

As described herein, the partially dried inkjet media can provide difficulties when stacking, aligning, and/or finishing. By including a conditioner 808 within the print engine 802, the partially dried inkjet media can be dried at a relatively faster rate without increasing a foot print of the system 800. In addition, including the conditioner 808 within the print engine 802 can allow standard devices (e.g., paper handling accessories, etc.) to be coupled to an output 816 of the system 800.

FIG. 9 illustrates an example system for a heated pressure roller consistent with the present disclosure. In some examples, the system 908 can be utilized as a conditioner for partially dried inkjet media 906. In some examples, the system 908 can apply pressure on a first side of the partially dried inkjet media 906 and apply heat on a second side of the partially dried inkjet media 906. In some examples, the system 908 can increase drying and/or evaporation of printing fluid applied to the partially dried inkjet media 906.

In some examples, the system 908 can receive partially dried inkjet media 906 at an input of the system 908 (e.g., illustrated as left side as referenced in FIG. 9). In some examples, the system 908 can include a pressure roller 908-1 to apply pressure on a first side of the partially dried inkjet media 906 (e.g., illustrated as top side as referenced in FIG. 9). In some examples, the pressure roller 908-1 can include a contact zone 960. The contact zone 960 can be an area on the pressure roller 908-1 that interacts with the first side of the partially dried inkjet media 906. In some examples, the contact zone 960 can correspond to a pressure platen 962 positioned within a heated roller 908-2.

In some examples, the heated roller 908-2 can apply heat to a second side of the partially dried inkjet media 906 (e.g., illustrated as bottom side as referenced in FIG. 9). In some examples, the heated roller 908-2 can include a heat source 966 to generate heat. The heat source 966 can include a number of different heat sources. For example, the heat source 966 can include a resistive element, an inductive coil, and/or a halogen heat source. In some examples, the heat source 966 can generate heat that is transferred to a heat transfer belt 964. In some examples, the heat transfer belt 964 can rotate around the heated roller 908-2 and contact the second side of the partially dried inkjet media 906 within the pressure platen 962.

The above specification, examples and data provide a description of the method and applications, and use of the system and method of the present disclosure. Since many examples can be made without departing from the spirit and scope of the system and method of the present disclosure, this specification merely sets forth some of the many possible example configurations and implementations.

What is claimed:

1. A partially dried inkjet media conditioner, comprising:
a print engine that encases a print zone within a housing;
and
a media path coupled to a position of a dryer zone between an input and an output of the dryer zone to provide partially dried inkjet media from the dryer zone to a conditioner within the print engine, wherein the conditioner comprises a heated pressure roller and wherein an output of the conditioner is separate from the output of the dryer zone.

16

2. The conditioner of claim 1, wherein the heated pressure roller applies pressure to a first side of the partially dried inkjet media and heat to a second side of the partially dried inkjet media.

5 3. The conditioner of claim 1, wherein the heated pressure roller comprises a first roller that includes a contact zone that applies pressure to a first side of the partially dried inkjet media.

10 4. The conditioner of claim 3, wherein the heated pressure roller comprises a second roller that includes a heat source and a heat transfer belt to apply heat to a second side of the partially dried inkjet media.

15 5. The conditioner of claim 1, wherein the heated pressure roller increases evaporation of printing fluid applied to the partially dried inkjet media by the print zone.

6. A system for a partially dried inkjet media conditioner, comprising:

a housing;

a print engine disposed in the housing, wherein the print engine encases a print zone;

a first media path to provide partially dried inkjet media from the print zone to a dryer zone within the print engine; and

a second media path coupled to a position of the dryer zone between an input and an output of the dryer zone to provide the partially dried inkjet media from the dryer zone to a conditioner within the print engine, wherein the conditioner comprises a heated pressure roller, the output of the dryer zone is coupled to a duplex zone, and wherein an output of the conditioner is separate from the output of the dryer zone.

7. The system of claim 6, wherein the heated pressure roller is positioned above the print zone within the print engine.

8. The system of claim 6, wherein the second media path is coupled to an output of the dryer zone.

9. The system of claim 6, wherein the heated pressure roller comprises a vertical orientation with a pressure roller positioned to receive a first side of the partially dried inkjet media and a heated roller positioned to receive a second side of the partially dried inkjet media.

10. The system of claim 6, wherein the heated pressure roller is positioned above the dryer zone.

11. A system for a partially dried inkjet media conditioner, comprising:

an inkjet print engine that encases an inkjet print zone; a first media path to provide partially dried inkjet media from the inkjet print zone to a dryer zone within the inkjet print engine;

a second media path coupled to a position of the dryer zone between an input and an output of the dryer zone to provide the partially dried inkjet media from the dryer zone to a conditioner positioned above the print zone and the dryer zone within the print engine, wherein the conditioner comprises a heated pressure roller, the output of the dryer zone is coupled to a duplex zone to return the partially dried inkjet media to the print zone, and wherein an output of the conditioner is separate from the output of the dryer zone; and a third media path to provide the partially dried inkjet media from the conditioner to an output zone.

12. The system of claim 11, wherein the output zone is positioned below the conditioner.

13. The system of claim 11, wherein the heated pressure roller comprises a horizontal orientation with a pressure roller positioned to receive a first side of the partially dried

17

inkjet media and a heated roller positioned to receive a second side of the partially dried inkjet media.

14. The system of claim **11**, wherein the conditioner is removable from the inkjet print engine.
